UNITED STATES PATENT OFFICE,

HOMER F. NORTHRUP, OF WATERBURY, CONNECTICUT, ASSIGNOR TO THE
WATERBURY CLOCK COMPANY, OF SAME PLACE.

STRIKING CLOCK.

SPECIFICATION forming part of Letters Patent No. 337,784, dated March 9, 1886.

Application filed July 14, 1884. Serial No. 137,737. (No model.)

To all whom it may concern:

Be it known that I, HOMER F. NORTHRUP, residing at Waterbury, in the county of New Haven and State of Connecticut, have invented 5 certain new and useful Improvements in Striking Mechanism for Clocks; and I do declare the following to be a full, clear, and exact description of the same, reference being had to the accompanying drawings, which form a part 10 of this specification.

Heretofore the lifts, warns, count-hooks, and stops of the striking parts of clocks have each been made from separate pieces of wire or embodied in several pieces of sheet metal. Such 15 constructions are objectionable, in that the pieces or parts are not positive and reliable in action, in that they are liable to derangement, in that they are expensive to construct and organize, and in that they require adjusting and fitting to each clock.

With the end in view of obviating the objections above enumerated, my invention comprehends an improved part for the striking mechanism of clocks; and it consists in a single piece of sheet metal having a lift, a warn, 25 a count-hook, and a stop.

My invention further consists in certain details of construction, as will be hereinafter described, and pointed out in the claims.

30 In the accompanying drawings, Figure 1 is a view in elevation of one form which my improved part may assume, shown in a clock-movement having its front plate partly broken away; and Fig. 2 is a detached view, in perspective, of such part.

As herein shown, my improved part consists of a single piece of sheet metal embodying a lift, A, consisting of a long arm terminating in a beveled finger, Q, a main arm, N, an extension, M, offsetting from the lower face of the same, a warn, B, and a stop, D, respectively, consisting of fingers extending inwardly at right angles from the said extension, and the former being located in the rear of and 45 extending above the level of the latter, and a count-hook, C, located at the end of the said main arm and at right angles therewith. The said improved part is secured to a collet, G, mounted upon an arbor, H, located between 50 the plates E and F of a clock-movement pro-

vided with a double lift-cam, L, which engages with the lift A of the said part, with a wheel, P, carrying a pin, O, which engages with the warn and stop of the part, and with a wheel, K, carrying a count-wheel, J, which is engaged by the count-hook of the part. A coiled spring, I, encircling the arbor H and having its ends respectively connected with the rear plate of the movement and the lift of my improved part, holds the same in position for operation.

By reason of its length and through its beveled finger the lift of my improved part is readily sprung aside for turning back the hands of the clock, while by constructing and relatively 65 arranging the warn and stop as shown the warning and stopping of the striking part of the clock is effected through a single pin carried by one of the wheels of the striking-train, which is thus simplified in construction and 70 operation.

Having fully described one form which my improved part may assume, I will now proceed to set forth the mode of its operation in connection with the movement shown, which 75 strikes the hours when the count-hook is depressed between the teeth of the count-wheel, and the half-hours when it is engaged with their flat extended faces.

Normally the pin O is engaged with the stop 80 D of the improved part, from which it is released, a few minutes before striking, by the lift-cam acting through the lift of the improved part and raising the same, whereby the pin is released from the stop as aforesaid, and that 85 actuation of the train permitted which is required for bringing the parts into position for immediate striking. This adjustment of parts having been effected, the train is arrested by the interception of the pin by the warn of the 90 improved part. When the time for striking arrives, the lift-cam passes the lift of the improved part, the same is depressed, the pin released from the warn, the train started, and the hour, whatever it may be, is struck, after 95 which the train is stopped through the count-wheel, which elevates the said improved part into position for intercepting the pin by its stop. As to the striking of the half-hours, when the lift-cam passes on the half-hour the lift 100

of my improved part, the same will be upheld in position for the interception of the pin by the stop after the half-hour has been sounded by that tooth of the count-wheel upon which 5 the count-hook of my improved part was left after striking the preceding hour.

By embodying the lift, warn, count-hook, and stop of the striking part of a clock in a single piece of metal, positiveness and reliability of action in such parts are obtained and their derangement avoided by reason of their integral relationship, and an obvious economy of time, labor, and outlay for tools in the construction of the striking parts of clocks is effected. Moreover, my improved part, being made of sheet metal and in one piece, can be produced in perfect duplication and handled without distortion, and hence requires no adjusting or fitting in being assembled with the 20 other parts of a striking mechanism.

Having fully described my invention, what

I claim as new, and desire to secure by Letters Patent, is—

1. In the striking part of a clock, a single piece of sheet metal having a lift, warn, count-hook, and stop, the warn and stop being bent at right angles to the body of the piece, substantially as set forth.

2. In the striking part of a clock, a single piece of sheet metal embodying a lift, warn, 30 count-hook, and stop, the warn and stop offsetting from that arm of the device carrying the count-hook thereof, substantially as set forth.

In testimony whereof I have signed this 35 specification in the presence of two subscribing witnesses.

HOMER F. NORTHRUP.
